(57) CLAIM

The ornamental design for a utensil handle, as shown.

DESCRIPTION

FIG. 1 is a perspective view of the utensil handle of the invention;

FIG. 2 is a top plan view thereof;

FIG. 3 is a rear elevational view thereof;

FIG. 4 is a front elevational view thereof; and,
FIG. 5 is a side elevational view thereof, the opposite side of which is an identical mirror image.

The broken line showings in FIGS. 1, 3 and 4 are for illustrative purposes only and form no part of the claimed design.
